(57) **CLAIM**

The ornamental design for a lavatory bowl, as shown and described.

DESCRIPTION

FIG. 1 is a perspective view of a lavatory bowl of the present invention showing my new design;

FIG. 2 is a front elevational view of the lavatory bowl of FIG. 1;

FIG. 3 is a top plan view of the lavatory bowl of FIG. 1; FIG. 4 is a rear elevational view of the lavatory bowl of FIG. 1; and,

FIG. 5 is a left end elevational view of the lavatory bowl of FIG. 1, the right end elevational view being a mirror image thereof.

The bottom view is not ornamental and forms no part of the claimed design. Broken lines in the drawings are used to show environment, but form no part of the claimed design.
